F. J. VERBA,
LARYNGOSCOPE,
APPLICATION FILED DEC. 15, 1915.

1,190,050.

Patented July 4, 1916.

UNITED STATES PATENT OFFICE.

FRANK J. VERBA, OF COLORADO SPRINGS, COLORADO.

LARYNGOSCOPE.

1,190,050.

Specification of Letters Patent. Patented July 4, 1916.

Application filed December 15, 1915. Serial No. 67,014.

To all whom it may concern:

Be it known that I, FRANK J. VERBA, a citizen of the United States, and a resident of Colorado Springs, in the county of 5 El Paso and State of Colorado, have invented a new and useful Improvement in Laryngoscopes, of which the following is a specification.

My invention is an improvement in laryngoscopes, and the invention has for its 10 object to provide a device of the character specified especially adapted for treating tubercular affections of the larynx by the direct application of sun rays to the diseased 15 parts, and wherein the device is so arranged and constructed that the patient may treat himself by either reflection, that is, conveying the healing and anesthetic infra-red rays into the larynx; or by refraction, that is, 20 by conveying the germ destroying ultra-violet or actinic rays in the same manner.

In the drawings:—Figure 1 is a front view of the improved laryngoscope, Fig. 2 is a side view at right angles to Fig. 1, Fig. 25 3 is a top plan view, and Figs. 4 and 5 are sections on the lines 4—4 and 5—5, respectively, of Fig. 2, each view looking in the direction of the arrows adjacent to the line.

In the embodiment of the invention shown 30 in Figs. 1 to 5 a substantially U-shaped frame is provided, consisting of a body 1 and arms 2 and 3, extending laterally from the body in the same direction and in spaced parallel relation.

35 A double convex lens 4 arranged within the circular frame 5 in the usual manner is connected with the body 1 of the frame, a staff or handle 6 being connected to the frame 5 of the lens. This staff or handle is provided with an angular portion 7 which engages a nipple 8 on the frame, and the staff or handle 6 is mounted to slide in a sleeve 9, connected with the frame in a manner to be presently described, and the staff 40 is held in adjusted position with respect to the sleeve by a set screw 10, which is threaded through the sleeve into engagement with the staff.

The sleeve is provided with a radial arm 45 having a ball 11 at the free end thereof, and this ball 11 is engaged between parallel clamping plates 12. The ball 11 is at one end of the said plates and at their other end the plates 12 are arranged on opposite sides 55 of the body 1 of the frame 1—2—3, and the plates are clamped on the body and on the

ball by a set screw 13, which is rotatably mounted in one of the plates and has a threaded engagement with the other. It will be obvious that with this arrangement 60 the position of the staff with respect to the frame may be varied and when the parts are in adjusted position the clamping plates 12 may be clamped on the ball and the body to hold the parts in said adjusted position. 65

A concave mirror 14 is mounted on the arm 2 of the frame, the said mirror being connected with a staff or handle 15, by means of a clamp corresponding to the clamp 12—13, just described. The mirror 14 is provided on its convex face with an arm extending laterally from the mirror, and having a ball 16 at its free end. The staff or handle 15 is provided with a similar ball 17, and clamping plates 18 similar to the 75 plates 12 are engaged with the balls, the plates being on opposite sides of the balls and being clamped on the balls by a set screw 19. The set screw is journaled in one of the plates and has a threaded engagement 80 with the other.

A flat mirror 20 is mounted on the arm 3 of the frame, the mirror being connected to a staff or handle 21 in the same manner as the mirror 14 is connected to the staff or 85 handle 15. The mirror has a ball 22 similar to the ball 16 and similarly mounted, and the staff or handle has a ball 23. These balls are clamped between plates 24, corresponding to the plates 12 and 18, and the plates are 90 clamped on the balls by a set screw 24.

The plates 12—18—24 are similar in one respect, namely, each plate is recessed at its ends and on its inner face to receive the balls. In the case of the plates 12 the recesses for receiving the body are transverse grooves, the other recesses being merely rounded depressions. Each of the staffs or handles 15 and 21 is adjustably connected with the arms 2 and 3 of the frame by means 100 of a sleeve 25. Each of these sleeves 25 as shown more particularly in Fig. 4 is mounted to slide on the arm of the frame, and each sleeve is held in adjusted position by means of a set screw 26, each set screw being threaded through an opening in the sleeve into engagement with the frame arm. 105

The staffs or handles 15 and 21 are slidably connected with the sleeves as shown in Fig. 4. A clamping block 27 is arranged 110 at one side of each sleeve and each of the said blocks is adjustably connected to the

sleeve by means of a set screw 28. Each of the set screws 28 is journaled in an opening in the block and engages an internally threaded opening in the sleeve.

5 Each block is grooved transversely to receive the staff 15-21 as the case may be, and since each block is in effect pivoted to the sleeve by the set screw 28 it will be obvious that either staff or handle may be 10 swung at an angle with respect to the sleeve as indicated in dotted lines for the staff 21 in Fig. 2. The staffs or handles may be also adjusted longitudinally by loosening the set screw 28 and they may be adjusted 15 vertically with respect to the frame by loosening the set screw 26.

Means is provided in connection with the frame 1-2-3 for permitting the same to be connected with a chair back for instance, 20 to support the frame in upright position. The said mechanism comprises a clamping bar or rod 29 connected with each arm 2 and 3 of the frame. Each of the said bars or rods 29 has its upper end offset toward 25 the frame arm as indicated at 30, and the said upper end is received in one of the openings of a double sleeve 31. This sleeve has two parallel openings, one of which is engaged by the adjacent arm 2 or 3, as the case may be, while the other is engaged by the offset portion of the adjacent bar or rod.

Set screws 32 and 33 are threaded through the sleeves at opposite sides thereof 35 for engaging the arm 2 or 3 of the frame and the offset portion of the clamping bars, and it will be noticed that the lower end of the bars 29 and of the arms 2 and 3 are bent outward to facilitate their engagement 40 with the chair back indicated in dotted lines in Fig. 2.

When the set screws 32 and 33 are tightened on the bars and on the arms the said bars 29 are held in spaced parallel relation 45 with respect to the arms, and the said bars form a species of clamp for permitting the frame to be supported in the manner mentioned. Each of the mirrors 14 and 20 is connected to its staff or handle 15 or 21 by 50 a universal joint connection, and each of the said connections is capable of being rigidized or fixed so that the mirrors may be held in adjusted position. The same is true 55 as regards the connection between the staff or handle 6 and the frame.

While the joint 11-12-13 is a universal joint for purposes of adjustment it may be made a rigid joint when the adjustment desired has been attained. The height of the 60 mirrors with respect to the frame may be varied by means of the set screw 26, and the lateral relation of the said mirrors with respect to the frame as well as the lateral relation of the lens 4 may be varied by 65 means of the set screws 10 and 28. The

height of the frame 1-2-3 with respect to the surface of the ground may be varied by means of the clamp 29-30-31.

In use the mirror 14 is utilized to reflect the rays into the throat. The mirror 20 which is a plain mirror is provided to permit the operator to see and understand what he is doing, giving a reverse picture of the interior of the throat. In addition to reflecting the rays the mirror 14 also collects the rays, and causes them to be converged upon the point desired, that is, on the throat mirror when used or on the parts to be treated.

I claim:

1. A laryngoscope, comprising a substantially U-shaped frame, consisting of a body and arms depending from the body in spaced relation, a clamping bar slidably connected with the lower end of each arm and adjustable vertically with respect to the arm, a concave mirror supported by one arm and adjustable thereon, a plain mirror connected with the other arm and adjustable thereon, a lens having a handle or staff extending from one side thereof approximately perpendicular to the plane of the lens, and an adjustable connection between the staff and the body of the frame, said connection comprising a pair of clamping plates, the body of the frame being between the plates at one end thereof, a sleeve mounted to slide on the staff or handle of the lens and having a radially extending ball adapted to fit between the plates at the other end from the body, a set screw engaging the plates for clamping them on the body and the balls and a set screw threaded through the sleeve into engagement with the staff, a staff for each mirror, a universal joint connection between each mirror and the staff and having means for making the connection rigid with respect to both shaft and mirror, a sleeve slidable on the arm of the frame and having means for clamping the sleeve to the frame, a clamping block at each sleeve and having a transverse groove for receiving the adjacent staff on the face adjacent to the sleeve, and a set screw for connecting the block to the sleeve.

2. A laryngoscope, comprising a substantially U-shaped frame, consisting of a body and arms depending from the body in spaced relation, a clamping bar slidably connected with the lower end of each arm and adjustable vertically with respect to the arm, a concave mirror supported by one arm and adjustable thereon, a plain mirror connected with the other arm and adjustable thereon, a lens having a handle or staff extending from one side thereof approximately perpendicular to the plane of the lens, and an adjustable connection between the staff and the body of the frame, said connection comprising a pair of clamping plates, the body

of the frame being between the plates at one end thereof, a sleeve mounted to slide on the staff or handle of the lens, and having a radially extending ball adapted to fit between the plates at the other end from the body, a set screw engaging the plates for clamping them on the body and the balls, and a set screw threaded through the sleeve into engagement with the staff.

10 3. A laryngoscope, comprising a substantially U-shaped frame, consisting of a body and arms depending from the body in spaced relation, a clamping bar slidably connected with the lower end of each arm and adjustable vertically with respect to the arm, a concave mirror supported by one arm and adjustable thereon, a plain mirror connected with the other arm and adjustable thereon, a lens having a handle or staff extending 20 from one side thereof approximately perpendicular to the plane of the lens, and an adjustable connection between the staff and the body of the frame.

4. A laryngoscope, comprising a substantially U-shaped frame, consisting of a body and arms depending from the body in spaced relation, said arms having clamping means for engaging a fixed support, a support for the lens adjustably connected with the body of the frame, interchangeable lenses each having a staff for slidably engaging the support and the support having means for holding the staff in adjusted position, a mirror for each arm of the frame, 35 a staff for each mirror and having a universal joint connection with the mirror, means in connection with each joint for making the joint rigid, and an adjustable connection between each staff and arm of the frame for permitting the staff to be adjusted with respect to the arm.

5. In a laryngoscope, a substantially U-shaped frame, consisting of a body and arms extending from the body and having

means for engaging a fixed support, a supporting sleeve for receiving a lens supporting staff having a universal joint connection with the body of the frame, means in connection with the joint for making the said joint rigid, the lens supporting staff 50 being adapted to slide in the sleeve, means for fixing the staff in the sleeve, and mirrors adjustably connected with the frame.

6. In a laryngoscope, a substantially U-shaped frame, consisting of a body and 55 arms extending from the body and having means for engaging a fixed support, a supporting sleeve for receiving a lens supporting staff having a universal joint connection with the body of the frame, means in connection with the joint for making the said joint rigid, the lens supporting staff being 60 adapted to slide in the sleeve, means for fixing the staff in the sleeve, and mirrors adjustably connected with the frame. 65

7. In a laryngoscope, a substantially U-shaped frame, consisting of a body and arms extending from the body and having means for engaging a fixed support, a supporting sleeve for receiving a lens supporting staff having a universal joint connection with the body of the frame, means in connection with the joint for making the said joint rigid, the lens supporting staff being 70 adapted to slide in the sleeve, and mirrors adjustably connected with the frame. 75

8. In a laryngoscope, a substantially U-shaped frame comprising a body and arms extending from the body, and having means for engaging a fixed support, a mirror 80 adjustably connected with each arm of the frame, and means on the body of the frame for engaging and holding a lens supporting staff.
